UNITED STATES PATENT OFFICE.

JAMES B. WAGG, OF APPLETON, WISCONSIN.

PAPER-MAKING APPARATUS.

1,129,766.

Specification of Letters Patent. Patented Feb. 23, 1915.

Application filed April 2, 1914. Serial No. 229,099.

To all whom it may concern:

Be it known that I, JAMES B. WAGG, a citizen of the United States, residing at Appleton, in the county of Outagamie and State of Wisconsin, have invented new and useful Improvements in Paper-Making Apparatus, of which the following is a specification.

The present invention has reference to paper-making apparatus, and more especially to apparatus for reeling or winding up the web of paper after the same has been passed through the size bath and before it is subjected to the final drying.

It proposes certain hereinafter-described improvements whereby wrinkling, blistering and, above all, breaking of the web at the point where the actual winding takes place, is completely avoided.

An embodiment of the invention is illustrated in the accompanying drawing, whereof:

Figure 1 is a side illustration of the improved winding mechanism; Fig. 2 is a plan view of Fig. 1; Fig. 3 is an enlarged, fragmental view of one of the rolls; and Fig. 4 is a side elevation of a modification.

In said drawing, 1 indicates, generally, the strip or web of paper undergoing treatment, and 2 the bath of size through which the same is passed, after having previously been engine-sized and dried, as is usual. On leaving the size bath, the web is passed between the rolls 3 and 4, which serve both to feed it forward and to remove the excess size, and from these rolls it is led, while still wet, to the winding mechanism. The latter preferably consists of a rotating drum 5, whose shaft 6 has a cone or other suitable drive 7, and a reel 8 to which the web passes from the drum and on which it is wound up by reason of its frictional engagement with the same. In the construction shown, the ends of the drum shaft 6 fit in U-shaped bearings 9 whose stems are fastened to the tops of the standards 10 which constitute the drum support.

Between the feed rolls 3 and 4 and the winding mechanism are interposed instrumentalities which embody the most important features of the invention and which are employed both to tension and take up slack in the still wet web, and to hold the latter out of extended contact with the drum 5 in order to prevent said drum from exerting any sustained dragging or drawing action

thereon. In the construction represented in Figs. 1 and 2, separate rolls 11 and 12 are utilized for the purposes stated, and, between these rolls, a third roll 13. The roll 11, in this instance, constitutes the take-up and tension means, and is supported a slight distance above and in front of roll 4 in a pair of bearing blocks 14 formed with upwardly-opening sockets 15 for the reception of the roll ends. These blocks are slidably mounted upon a pair of vertical pins 16, and are yieldingly held in elevated position by expansible coil-springs 18, the said pins being connected in any desired manner to the trough or tub containing the size. The rolls 12 and 13 are carried by pairs of vertical supporting rods 19 and 20, suitably connected together and braced, the lower ends of the rods 19 being bent around and fastened to the bearings 9, while the corresponding ends of the rods 20 are fastened to the standards 10. The tops of these rolls are disposed above the top of drum 5 and slightly below that of roll 11, their relative arrangement being such that the top of roll 12 is a little lower than that of roll 13, so that the web has a very gradual downward inclination between the rolls 11 and 12.

The roll 12 acts as the means for guiding the web to the winding mechanism, and it is so positioned that the web passes from it in a perfectly straight line direct to the nip of the drum 5 and the reel 8, and, therefore, perpendicularly to an imaginary plane passing through the axes of the reel and drum, forming a true tangent to the peripheral surfaces of both reel and drum at the lines of intersection between the aforesaid plane and such surfaces, as will be understood. As the strain upon the web during drum winding is ordinarily greatest at the point where it passes around the drum, and varies according to the extent of contact between the web and the drum surface, (i. e., the surface area of contact), and, above all, since wet paper, being weaker, requires very much more careful handling than dry, it is apparent that by decreasing the area of surface contact between the web and drum to a minimum, the dragging action is reduced to a point where it is practically negligible, with proportionate avoidance of breakage. For the same reasons, wrinkling and blistering of the web, with resultant waste thereof, are avoided, owing to the employment of roll 11 and its arrangement as above indicated.

since the minimum contact area completely prevents the entrance and accumulation of air behind the web and between the same and the drum. It is preferable to construct 5 the said roll of brass in order that its surface may be highly finished. In the modification shown in Fig. 4, the same principle is involved, but the machine is simplified to a very considerable extent by omitting 10 the rolls 12 and 13, together with their supports, and utilizing the roll 11 to effect both the tensioning and guiding of the web. In such case, the web passes from roll 11, which may, therefore, have a highly-finished surface, directly to the winding mechanism, the latter being disposed comparatively close to the sizing bath and, if desired, below the floor level.

To enable reel 8 to be accurately positioned for the above purpose, as well as to permit the degree of pressure exerted by it upon the drum to be varied, in order to conform to existing conditions, any suitable device, such, for instance, that shown, may be 20 employed. In this form, the said device embodies a pair of upwardly-inclined arms 21, which constitute the reel support and which are pivoted at their lower ends to the standards 10, the upper ends of these arms 25 being connected by adjustable links 22 to the corresponding ends of a pair of similarly inclined arms 23 fixed to a horizontal shaft 24. The latter is actuated from a vertical controller shaft 25 through the 30 agency of worm gearing 26, the shaft 25 being equipped with a hand-wheel or other operating element 27. Rotation of the controller shaft thus effects a corresponding movement of shaft 24 and, in consequence, 35 a rocking movement, of arms 23, with the result that the inclination of the reel-carrying arms 21 is varied. After the reel has been filled, it is removed from its support, with the web in a wet state thereon, and 40 subjected to any further treatment desired.

Having fully described my invention, I claim:

1. In an apparatus for winding wet paper web, the combination with means for sizing 50 the web and size-expressing means operative to feed the wet web from the sizing means, of a revoluble cylindrical drum, a reel rest-

ing against the drum and operative to receive and wind the wet web into a roll, and web-guiding means interposed between the size-expressing means and said drum and reel and operative to direct the wet web to the line of nip between said drum and reel.

2. In an apparatus for winding wet paper web, the combination of means for wetting the web, and means for feeding the wet web forward therefrom, of a revoluble cylindrical winding drum, a reel resting against the drum for winding the wet web into a roll, and means interposed between said feeding means and said drum and reel and guiding the wet web directly to the line of nip between said drum and reel.

3. In an apparatus for winding wet paper web, the combination with means for wetting the web, and means for feeding the wet web forward therefrom, of a revoluble cylindrical winding drum, a reel resting against the drum for winding the wet web into a roll, and web-guiding means interposed between the web-feeding means and said drum and reel and operative to direct the said web to the line of nip between said drum and reel, said guiding means including a yieldable web-tensioning device.

4. In an apparatus for winding wet paper web, the combination with means for wetting the web, and means for feeding the wet web forward therefrom, of a revoluble cylindrical winding drum, a reel resting against the drum for winding the wet web into a roll, said drum and reel being located below the level of said feeding means, and guiding means embodying a yieldably-acting roll co-operative with the web at a point between said feeding means and the drum and reel and directing the web to the line of nip between said drum and reel and to maintain a yielding tension on the web.

In testimony whereof I have hereunto set my hand in presence of two subscribing witnesses.

JAMES B. WAGG.
